UNITED STATES PATENT OFFICE.

CLIFFORD J. THOMPSON, OF MIAMI, FLORIDA.

TURNBUCKLE.

1,317,605.

Specification of Letters Patent. Patented Sept. 30, 1919.

Application filed May 7, 1918. Serial No. 233,085.

To all whom it may concern:

Be it known that I, CLIFFORD J. THOMPSON, a citizen of the United States, residing at Miami, in the county of Dade and State 5 of Florida, have invented new and useful Improvements in Turnbuckles, of which the following is a specification.

This invention relates to improvements in turn buckles and is especially adapted for 10 use in connection with the stay wires of a flying machine, the primary object being to lock the turn buckle after it has been adapted so as to keep the wires taut.

It is also the object of the invention to 15 combine with the locking means further means for decreasing the wind resistance during the travel of the machine, thereby reducing the wind resistance by forming the locking means so as to fill the air pocket 20 created at the rear of the buckle, thereby preventing formation of a vacuum.

Other objects and advantages of the invention will appear when the following description is read in connection with the accompanying drawings, in which:—

Figure 1 is a view in elevation of a turn buckle constructed in accordance with the present invention, the ends of the stay wires being connected thereto.

Fig. 2 is a sectional view on the line 2—2 of Fig. 1.

Fig. 3 is a similar view on the line 3—3 of Fig. 1, and

Fig. 4 is a like view on the line 4—4 of Fig. 1.

Referring to the drawings in detail, wherein like characters of reference denote corresponding parts, the improved turn buckle, is designated in its entirety by the reference character 10, while at 11 is shown the adjacent ends of the stay wires such as are usually employed in the construction of an airplane or flying machine.

The turn buckle 10 includes a barrel 12, 45 which is provided with a longitudinal bore 13, the latter having at each end oppositely disposed threads 14, for engagement with the threaded shanks 15 of the eyes 16, to which the stay wires 11 are secured in the usual manner. The barrel is also provided 50 with a transverse opening 17 for the reception of a suitable implement for the purpose of adjusting the buckle.

Each of the shanks 15 has secured thereon 55 a ratchet disk 18, the teeth of each of these disks being reversely arranged. Secured to

or carried by the barrel 12 is a spring bar 18, the said bar being secured at approximately its central point with the ends 19 extending beyond the ends of the barrel 12. 60 These ends are provided with elongated teeth 20 which engage the teeth of the ratchet 18, the latter being of approximately the same diameter as the ends of the barrel 12 and the teeth extending within the diameter of the said barrel so as to provide a positive engagement. The spring bar is wedge shaped, that is, it is of triangular shape in cross section, the apex of the angle being outwardly disposed with respect to the 70 barrel 12. When in position this bar is arranged upon the rear of the machine facing away from the wind and acts to decrease the wind resistance due to the barrel 12 ordinarily forming a pocket and creating a 75 vacuum at the rear.

It will be seen that the foregoing invention provides a positive lock for the turn buckle by preventing any accidental relative movement of the parts after adjustment, due to vibrations permitting however, any future adjustment made necessary by the possible stretching of the wires 11.

The invention is susceptible of various changes in its form, proportions and minor 85 details of construction and the right is reserved to make such changes as fall within the scope of the appended claims.

Having described the invention, what is claimed is:—

1. A turn buckle embodying a barrel having a bore provided with right and left hand threads, eyes having threaded shanks engageable with said bore, a ratchet disk secured upon each of said shanks and a 95 spring tooth engageable with each of said disks to hold the parts against relative movement.

2. A turn buckle embodying a barrel having a bore provided with right and left 100 hand threads, eyes having threaded shanks engageable with said bore and resilient means carried by the barrel and engageable with means carried by the shanks whereby relative rotation of the shanks and barrel 105 may be provided in one direction only.

3. A turn buckle embodying a barrel having a threaded bore provided with right and left hand threads, eyes having threaded shanks engageable with said bore, a ratchet 110 disk secured upon each of said shanks, a spring bar carried by the barrel and ex-

tending longitudinally thereof and an elongated tooth located at each end of the bar and engageable with the disks to hold the parts against relative movement.

5 4. A turn buckle embodying a barrel having a bore provided with right and left hand threads, eyes having threaded shanks engageable with said bore, a ratchet disk secured upon each of said shanks, a spring bar

having a triangular cross sectional shape 10 and secured to the barrel with the apex of the triangle disposed outwardly and an elongated tooth located at each end of the bar and engageable with the disks to hold the parts against relative movement. 15

In testimony whereof I affix my signature.

CLIFFORD J. THOMPSON.
